UNITED STATES PATENT OFFICE.

FREDRICK HANSON AND CHARLES FREIHOFER, OF PHILADELPHIA,
PENNSYLVANIA.

DESIGN FOR A COVER FOR BAKE-PANS.

SPECIFICATION forming part of Design No. 33,583, dated November 20, 1900.

Application filed October 13, 1900. Serial No. 33,011. Term of patent 14 years.

To all whom it may concern:

Be it known that we, FREDRICK HANSON and CHARLES FREIHOFER, citizens of the United States, and residents of Philadelphia, Pennsylvania, have invented and produced a certain new and original Design for a Cover for Bake-Pans, of which the following is a specification.

Our design for the cover of a baking-pan is 10 fully illustrated in the accompanying drawings, in which—

Figure 1 is a plan view of our cover for baking-pans. Fig. 2 is a side view; and Fig. 3 is a section on the line 3 3, Fig. 1.

15 The essential feature of the design is the rounded body of the cover having the representation of a statue of William Penn in relief thereon.

A is the cover elongated, as shown, and having a rounded body portion *a* and a flange *b* at the base.

d is a figure pressed up from the body of the pan, representing William Penn.

We claim—

The design for a cover of a baking-pan as herein described and as illustrated in the accompanying drawings.

In testimony whereof we have signed our names to this specification in the presence of two subscribing witnesses.

FREDRICK HANSON.
CHARLES FREIHOFER.
